BOBBIN MAGAZINE FOR WEFT
REPLENISHING LOOMSRichard G. Turner, Worcester, Mass., assignor to
Crompton & Knowles Loom Works, Worcester,
Mass., a corporation of Massachusetts

Application June 28, 1947, Serial No. 757,875

7 Claims. (Cl. 139—245)

1

This invention relates to improvements in weft replenishing looms and it is the general object of the invention to provide an improved reserve bobbin magazine.

The diameter of the weft wound on the reserve bobbins in a weft replenishing mechanism may be larger than, equal to, or smaller than the diameter of the bobbin butts. Furthermore, in the weaving of certain types of fabrics it is not permissible to have knots or the like in the weft because of blemishes which they would produce in the finished fabric. When the yarn breaks during the winding of a bobbin to be used in the weaving of such fabrics the bobbin is removed from the winding machine and sent to the loom, even though the bobbin be only partly wound. Under such conditions the magazine will contain bobbins some of which are fully wound and others of which have only a short mass of weft thereon. The full and partly wound bobbins, regardless of their weft diameter, will not stack properly, and the upper bobbins will have their tips so far below their butts that they fall out of the magazine.

It is an important object of the present invention to provide a bobbin magazine with readily adjustable guideways for both the butts and tips of the bobbins so that by a simple manual operation the weaver can adjust the widths of the guideways to a condition which will enable the bobbins to lie substantially horizontally and therefore feed downwardly toward transfer position without falling out of the magazine. Thus, if several partly filled bobbins are in the magazine the tip guideways can be made narrow to raise the tips and prevent objectionable tilting of the upper bobbins.

Since the bobbin conditions change from time to time as new bobbins are placed in the magazine it is desirable that the widths of the guideways be readily adjustable, and it is a further object of the invention to accomplish this result by means of yielding locks which can be moved quickly and easily to alter the widths of the guideways.

In the weaving of fabrics requiring two shuttles a rocking magazine may be employed which can be shifted to place the lowest bobbin in either of the two bobbin stacks in transfer position. This requires a pivot for the magazine and also generally requires that the outer or bobbin tip engaging plate of the magazine be supported from the inner or butt engaging plate of the magazine. When magazines of this type are made large enough to accommodate a considerable number of bobbins it is found that the outer plate tends

2

to vibrate, and to correct this condition it is a further object of the present invention to provide anti-vibration guides, such as rolls, positioned to engage the inner plate of the magazine.

5 It is occasionally desirable to be able to effect slight adjustments in the vertical position of the magazine and to accomplish this result it is a further object of the present invention to form the aforesaid pivot of the magazine as an eccentric 10 to enable the magazine to be raised or lowered to place the bottom bobbins in transfer position correctly with respect to the shuttle on the lay. Any horizontal displacement of the lower end of the magazine caused by adjustment of the eccentric 15 can be corrected by adjustable stops which determine the two extreme angular positions to which the magazine can be swung.

With these and other objects in view which will appear as the description proceeds, my invention 20 resides in the combination and arrangement of parts hereinafter described and set forth.

In the accompanying drawings, wherein a convenient embodiment of my invention is set forth,

Fig. 1 is a side elevation partly in section of the 25 forward part of a loom equipped with a magazine made according to the present invention,

Fig. 2 is an enlarged front elevation of the magazine looking in the direction of arrow 2, Fig. 1,

30 Figs. 3 and 4 are side elevations, partly in section, looking in the directions of arrows 3 and 4, respectively, of Fig. 2, Fig. 3 being enlarged,

Fig. 5 is an enlarged horizontal section on line 35 5—5 of Fig. 3 showing the adjustment for one of the butt guideways,

Fig. 6 is an enlarged horizontal section on line 6—6 of Fig. 1, showing the adjustment for one of the tip guideways,

Fig. 7 is an enlarged vertical section on line 40 7—7, Fig. 2,

Fig. 8 is a vertical section on line 8—8, Fig. 7,

Fig. 9 is an enlarged vertical section on line 9—9, Fig. 3,

Fig. 10 is a diagrammatic view showing the normal relation of bobbin butts and tips when the bobbins are fully wound, the weft and butt diameters being the same,

Fig. 11 is a diagrammatic front elevation of a 45 magazine containing partly filled bobbins as they appear before adjustment of the tip guideway, and

Fig. 12 is a view similar to Fig. 11 but showing the bobbin tips raised subsequent to reduction in the width of the tip guideway.

55 Referring to Fig. 1, the loom frame 10 has

mounted thereon a support 11 for the magazine designated generally at M. The latter is pivoted on a stud 12 extending through a hub 13 on the magazine support, see Fig. 9. The magazine has an inner or butt engaging plate 14 and an outer or tip engaging plate 15. Plate 14 has front and back bobbin butt guideways 16 and 17, respectively, while plate 15 has front and back bobbin tip guideways 18 and 19, respectively.

The bobbins B and B' in the two stacks feed down their respective front and back guideways by gravity toward transfer positions, one at the bottom of each of the bobbin stacks, as will be apparent in Fig. 3, to permit a transfer arm 20 to transfer the bobbin under it in transfer position into one or the other of two alternately active shuttles only one of which is shown at S. The shuttle when at the replenishing end of the loom occupies shuttle box 21 on lay L.

The bobbins have butts or heads 22, a mass of yarn Y, and tips 23. The lower part of the inner plate 14 is provided with a spacer lug 25 which separates the lowest bobbins of the two stacks, and front and back bobbin butt supports 26 and 27, respectively, may be mounted in usual manner to yield whenever the lowest bobbin in the associated guideway or stack is being transferred. In similar manner, the tips of the bobbins may be held by yielding supports 28 and 29 mounted pivotally on the outer magazine plate 15.

The magazine is ordinarily at rest in the position shown in Fig. 1, but can rock about stud 12. When a replenishing operation is to occur the magazine will remain in its normal position if the rear lowest bobbin B' is to be transferred, but if the lowest bobbin B is to be transferred the magazine will be rocked. The rocking mechanism includes a rod 30 pivotally connected to plate 14, a second rod 31 operated by the shifting shuttle box motion (not shown), and a bell crank lever 32.

Except as indicated hereinafter the matter thus far described may be of the usual construction and operates in the usual manner.

As already stated, the magazine can operate with various types of bobbins which, because of the diameter of their yarn masses or amount of yarn thereon, may not stack properly or feed properly down their guideways toward transfer position. The yarn diameter may be greater or less than the butt diameter or equal to it, and the bobbins may be either fully wound with weft extending practically the full length thereof, or only partly wound. The magazine may thus be supplied with an assortment of bobbins, some full and others only partly full. If a large number of partly full bobbins are present the tip ends of the upper bobbins will slant downwardly far enough so that they can roll out of the magazine and with such a group of bobbins it will be desirable to make the tip guideways narrow. If the yarn diameter is less than the butt diameter it will then be additionally desirable to widen the butt guideways.

In order to adapt the magazine for proper operation with these various types of bobbins I make each of the guideways adjustable as to width. Considering the forward butt guideway 16, for instance, the inner magazine plate 14 is formed with an integral flange or wall 35 for the right hand parts of the bobbin butts in the left stack as viewed in Fig. 3, and the lower left part of guideway 16 may also be defined by a second integral flange or wall 36. The upper left hand part of the guideway, however, is formed by a

movable wall 37 the lower end of which is pivoted as at 38 to the plate 14.

The upper part of the movable wall 37 is held in position by means shown more particularly in Fig. 5. The plate 14 is provided with a horizontal slot 40 and a series of holding teeth 41 on the inner or left hand side thereof, as viewed in Fig. 2. The wall 37 has a flange 42 lying flat against the surface 43 of plate 14. Bolt 45 passes through the flange 42 and slot 40 and has its outer end surrounded by a compression spring 46 located in the cylindrical shell or cup 47 of a yielding lock or holding member 48. The latter has teeth 49 which are normally urged into holding relation with teeth 41 by the spring.

The movable back wall 50 for the rear guideway 17 is similar to the wall 37 except that its pivot 51 is lower than pivot 38. It is also held adjustably in position by mechanism similar to that shown in Fig. 5.

In like manner, the outer magazine plate 15 is provided with adjustable front and back walls 55 and 56, respectively, to cooperate with flanges or walls 57 and 58, respectively, integral with plate 15 to define the bobbin tip guideways. The walls 55 and 56 are pivoted as at 60 and have bolts 61, see Fig. 6, provided with the same character of fittings shown in Fig. 5 and passing through slots 62 in plate 15.

From the matter thus far described it will be apparent that each of the adjustable walls 37, 50, 55 and 56 can be moved readily from one position to another merely by movement of the adjustable clamping or locking members 48 in directions to release teeth 49 from teeth 41. After the walls have been moved to their new positions the members 48 can be released, whereupon their springs will reengage teeth 41 and 49 to hold the movable walls in their adjusted positions.

Diagrammatic Fig. 10 shows the normal arrangement of the bobbins when they are all fully wound and of a given weft diameter, as for instance when the latter equals the butt diameter. Both the butt and tip guideways will be flared so that their walls diverge upwardly to permit the bobbins to be staggered to prevent rolling due to loom vibration. If the bobbins should not all be fully wound, and two of them have short masses of weft as in Fig. 11, the top bobbins will be tilted and will tend to fall out of the magazine. Under these conditions the tip guideway will be too wide, and its movable wall will be moved toward the fixed wall, thereby causing the tips to rise as they come more nearly into vertical alignment. The bobbins will then be in positions such as shown in Fig. 12, and will be in proper position for correct downward feeding.

A similar adjustment can be made if the yarn diameters are larger than the butt diameters and some of the bobbins are only partly wound. If movement of the adjustable tip wall does not give all the correction needed the movable butt wall can be moved away from its fixed wall. These adjustments can be made even if the yarn diameter equals the butt diameter, provided some of the bobbins are only partly full of weft.

It will therefore be seen that full and partly wound bobbins can be placed in the magazine stacks in any order and the movable walls adjusted to effect substantial horizontal alignment of the bobbins. These adjustments are able to move the bobbins as described due to the fact that the butt and tip guideways are normally flared upwardly, thus permitting adjustment of

the movable walls toward their fixed walls. The inner and outer magazine plates are held together by a brace 65 having feet 66 secured to the plates and joined by a horizontal section 67 the length of which determines the distance between the magazine plates. The feet are suitably secured to their respective places as at 68 so that the outer plate 15 derives its entire support from the inner plate 14.

The second feature of the invention relates to steadyng or vibration preventing means for the magazine. As shown in Figs. 3 and 7, the magazine support 11 is provided with two anti-vibration members 70 made as shown in Fig. 8. Each support has a shank threaded into the support 11 and held in adjusted longitudinal position by a lock nut 71. The end of each member 70 adjacent to the inner magazine plate 14 is provided with a ball 72 which bears against an anti-friction plate 73 secured to the magazine plate and rolls freely in its socket 69 when the magazine rocks. These members 70 are located a considerable distance below the pivot stud 12 and when properly set to engage plate 73 prevent objectionable vibration of the magazine, particularly the outer plate. Obviously other forms of anti-friction devices than the balls 72 can be utilized, but whatever form the members 70 take the magazine when rocked incident to a replenishing operation will be caused to move with a minimum of twisting, and the lowest bobbins B and B' will be parallel to the shuttle box 21.

The rod 30 is connected to the magazine at a point not far removed from the steadyng members 70 and this relationship results in proper movement of the outer magazine plate 15 when the magazine is rocked. A spring 74 acts to return the magazine to normal position subsequent to swinging by rod 30.

The third feature of the invention relates to the vertical adjustment of the magazine. As shown in Fig. 7, support 11 is provided with a stopping lug 15 which is adapted for engagement with one or the other of the front and back stop screws 76 and 77, respectively, which are mounted on the inner magazine plate 14. These screws are adjustable so as to determine the correct transfer positions of the lowest bobbins in the front and back stacks.

The previously described stud 12 has a shank 80 rockable in the hub 13 and has an eccentric end 81 passing through a hub 82 on the inside magazine plate 14. Nut 84 clamps the hub 82 against shoulder 85 of stud 12 and lock nut 86 holds the setting. The nuts when loosened permit turning of stud 12 so that the eccentric 81 can cause rising or falling of the magazine as a whole. As shown in Fig. 9 the magazine is in its lowest position adaptable to small weft diameters, but the magazine would be raised to provide added clearance if large diameter wefts are wound on the bobbins. If there should be any back and forth movement of the magazine due to turning of the eccentric the adjusting screws 76 and 77 can be altered to locate the lowest bobbins in the magazine correctly for transfer.

From the foregoing it will be seen that I have provided a magazine wherein bobbins of various amounts of weft wound thereon can be aligned so they will remain in the magazine and feed downwardly in their stacks toward transfer position. Any one of several assortments of bobbins can be placed in the guideways at random and when so placed the movable guideway walls can

be adjusted as described to establish the widths of the guideways best suited to the bobbins. While the movable guideway walls have been described in connection with a particular kind of holding device, such as the members 48, I do not wish necessarily thus to be limited, since any suitable holding means by which the adjusted widths of the guideways may be retained will serve the purpose of the present invention. It will also be noted that the steadyng members 10 are adjustable toward and from the magazine and are at a considerable distance below the pivot stud 12 and not far from the point at which a turning force is applied to the magazine by rod 30. Wear plate 73 is not essential but is desirable. Also, the eccentric stud 12 permits a vertical adjustment of the magazine with respect to the shuttle box, and the adjustable stop screws 76 and 77 afford compensation for any back and forth misplacement of the lowest bobbins in the magazine resulting from adjustment of the eccentric.

Having thus described my invention it will be seen that changes and modifications may be made therein by those skilled in the art without departing from the spirit and scope of the invention and I do no wish to be limited to the details herein disclosed, but what I claim is:

1. In a weft replenishing mechanism provided with bobbins which feed by gravity toward a transfer position, a guideway on said mechanism for the butts of the bobbins, a guideway on said mechanism for the tips of the bobbins, and means associated with each guideway for increasing or decreasing the width thereof to permit bobbins in said guideways having varying amounts of weft wound thereon to assume substantially horizontal positions.

2. In a weft replenishing mechanism provided with a stack of bobbins which move by gravity toward a horizontal transfer position, means on the mechanism defining a guideway for the butts of the bobbins, other means on the mechanism defining a guideway for the tips of the bobbins, and adjusting means by which the width of each guideway may be varied independently of the width of the other guideway for the purpose of causing bobbins having unequal amounts of weft wound thereon and which would normally be objectionably inclined to move toward horizontal positions.

3. In a weft replenishing mechanism operating with a plurality of bobbins which move by gravity toward a horizontal transfer position, a wall permanently attached to said mechanism and forming one side of a bobbin butt guideway, a movable wall adjustably mounted on said mechanism forming the other side of said guideway for the butts of the bobbin, a second wall permanently connected to the mechanism forming one side of the guideway for the tips of the bobbins, and a second movable wall adjustably mounted on said mechanism forming the other side of the guideway for the tips of the bobbins, said adjustable walls being capable independently of each other of assuming a plurality of positions with respect to their corresponding permanent walls to the end that bobbins in said guideways having varying amounts of yarn wound thereon and normally tending to have the tip ends below their butt ends may be caused to move toward horizontal positions.

4. In a weft replenishing loom operating with a plurality of bobbins having varying amounts of weft wound thereon and all movable toward a

horizontal transfer position by gravity, two walls permanently fixed with respect to the mechanism and forming one side each of a bobbin butt guideway and a bobbin tip guideway, and two other walls forming the other sides of said butt and tip guideways mounted for movement relatively to the permanently fixed walls corresponding thereto and independently of each other to the end that the widths of both guideways may be adjusted for the purpose of causing said bobbins to move from inclined positions toward horizontal positions.

5. In a weft replenishing mechanism operating with a plurality of bobbins having unequal amounts of weft wound thereon and tending to move by gravity toward a common horizontal position, two permanently fixed walls on the mechanism, one for a bobbin butt guideway and the other for a bobbin tip guideway, an adjustable wall on the mechanism for each guideway, and readily releasable manually operable holding means for each adjustable wall whereby the latter can be moved relatively to the corresponding permanently fixed wall for the purpose of readily varying the relative widths of said guideways to the end that the tip ends of the bobbins can be raised relatively to their corresponding butt ends.

6. In a weft replenishing mechanism provided with bobbins which feed by gravity toward a transfer position, a guideway on said mechanism for the butts of the bobbins, a guideway on said

mechanism for the tips of the bobbins, and adjusting means by which the width of the bobbin tip guideway can be reduced to raise the tips of the bobbins when some of the latter are fully wound with weft and others are partly wound with weft.

7. In a weft replenishing mechanism provided with bobbins which feed by gravity toward a transfer position, a bobbin butt guideway having walls normally diverging upwardly, a bobbin tip guideway also having walls normally diverging upwardly, said walls normally causing the bobbins to be staggered relatively to each other, and means to adjust the width of each guideway to the end that the width of the bobbin tip guideway can be reduced if some of the bobbins are only partly wound with weft and the width of the bobbin butt guideway can be increased if the diameter of the yarn is less than the diameter of the butts.
